UNITED STATES PATENT OFFICE.

REINHOLD FROMHOLZ, OF BOXHAGEN, GERMANY.

TALKING-MACHINE.

1,075,708.

Specification of Letters Patent.

Patented Oct. 14, 1913.

Application filed October 12, 1910. Serial No. 586,812.

To all whom it may concern:

Be it known that I, REINHOLD FROMHOLZ, a subject of the German Empire, and a resident of Gärtnерstrasse 19, Boxhagen, Germany, have invented a certain new and useful Improvement in or Relating to Talking-Machines; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

15 My invention relates to talking machines and aims to provide an improved means for attaching the sound box to the sound arm, and also aims to improve the quality and increase the volume of sound.

20 While it is desirable that sufficient weight or pressure should be applied to or carried by the needle to cause it to follow accurately all the indentations both vertical and lateral, of the sound groove, in the sound record, in 25 order that an accurate and satisfactory reproduction thereof may be produced, the common construction of talking machines, wherein the sound arm is adapted for both lateral and vertical movement is unsatisfactory because the weight of the sound arm upon the needle is usually more than is necessary to cause the needle to follow the sound groove properly and is, in part at least, the cause of the loud scratching noise 35 which is so noticeable while the machine is in motion and which is so disagreeable. This trouble may be obviated to a large degree by so constructing the sound arm that it is capable of horizontal or lateral movement only, thereby removing the weight of the arm from the needle, and by providing the small end of said arm with an angular section capable of a vertical motion relative thereto, and to which the sound box may be 40 attached. This construction, however, still leaves a section of the sound arm capable of free vertical movement and the weight of said section is carried by the needle as it travels over the record, producing to an undesirable degree, the scratching noise referred to.

45 My invention aims, so far as possible, to relieve the sound box of all unnecessary weight, thus reducing to a minimum the 50 scratching sound which has been referred to,

as so objectionable and thereby improving materially the quality of the sound.

In the embodiment of my invention illustrated and described herein Figure 1 is a side elevation of a talking machine, Fig. 2 a detail of the small end of the sound arm showing how the position of the sound box may be adjusted for more convenient removal and insertion of the needle therein, Fig. 3, a modified construction of the invention, Fig. 4, a vertical end view of the sound arm on the line 4-4, Fig. 5, and Fig. 5 a plan of the small end of the sound arm and sound box.

55 Referring to Fig. 1, the case A is provided with a suitable horn a, which is supported at its smaller or lower end by a bracket b, secured in turn to the case A. A sound arm c is secured to the bracket b, the large end thereof being disposed substantially opposite the small end of the horn a, providing a continuation or extension thereof, said arm c being capable of horizontal movement only, so that it may be brought into position over the disk table d of the 60 machine, the weight thereof, however, being carried by the bracket b. At its small end, Fig. 5, the sound arm c is given a lateral turn to receive the sound box e. The sound box may be of usual construction with respect to the diaphragm and needle, but it is preferably adapted to be mounted directly on the sound arm eccentrically with relation thereto, as shown in Figs. 1, 2 and 5. This arrangement improves the quality of the 65 sound materially. Another advantage arising from this construction is that when so mounted the weight of the sound box exerts the necessary pressure upon the needle to cause it to follow the groove of the disk 70 accurately without exerting sufficient pressure thereon to cause the disagreeable scratching sound referred to. For detachably securing the sound box e to the sound arm I provide, Fig. 4, a flange f having at 75 a suitable point thereon a stop f¹ and a recess f². The sound box is provided on the back thereof, Figs. 4 and 5, with a short neck g adapted to enter the end of the lateral portion of the sound arm and said box is 80 provided with a pin g¹ having a head g² to engage the flange f of the sound arm. To secure said sound box to said arm end the neck g of the sound box e is inserted into 85 the end of the arm with the head g² of the 90 pin g¹ engaged in the flange f. The sound box 95 is secured to the sound arm by the pin g¹ and the neck g of the sound box e is inserted into the end of the arm with the head g² of the 100 pin g¹ engaged in the flange f. The sound box 105 is secured to the sound arm by the pin g¹ and the neck g of the sound box e is inserted into the end of the arm with the head g² of the 110 pin g¹ engaged in the flange f. The sound box 115 is secured to the sound arm by the pin g¹ and the neck g of the sound box e is inserted into the end of the arm with the head g² of the pin g¹ engaged in the flange f.

pin g^1 opposite the recess f^2 . By turning the box e the head g^2 will engage the inner face of the flange f and if turned until said head g^2 engages said stop f^1 the box will be securely locked to the arm as if by a bayonet joint. If desired, the sound box may be concentrically mounted on the sound arm, see Fig. 3, and a suitable weight or pressure member h secured to the box to exert the necessary pressure upon the needle, or the sound box e may be so proportioned that it will supply the necessary pressure for the needle.

When it is desired to attach a needle to or remove it from the sound box it may conveniently be done by turning the sound box about the end of the sound arm until the needle holding means is in the position shown in Fig. 2.

It may be possible to vary the form of

my invention from the disclosure thereof herein without departing from the scope and spirit thereof.

Claim.

In a talking machine, a support, a sound arm thereon having lateral motion only, a flange on the outer end of said arm, a sound box provided with a neck eccentrically positioned thereon and adapted to be received directly by said arm, and a pin provided with a head on the back of said sound box, said head adapted to engage the edge of said flange to lock said box thereto and allowing rotation of said box on said arm.

In testimony whereof I affix my signature in presence of two witnesses.

REINHOLD FROMHOLZ.
